D. N. TRICKEY

SHAMPOOING APPARATUS

Filed May 11, 1927

INVENTOR.

DOROTHY N. TRICKEY,

BY

F. P. Gorin

ATTORNEY.

UNITED STATES PATENT OFFICE.

DOROTHY NELSEN TRICKEY, OF SEATTLE, WASHINGTON.

SHAMPOOING APPARATUS.

Application filed May 11, 1927. Serial No. 190,573.

This invention relates to an apparatus designed for use in treating human hair and particularly where such treatment involves the use of fluid preparations as in 5 washing, cleansing or coloring.

The main object of the present invention is the provision of an apparatus in which the head of the patient is inserted through an opening in an elongated, shallow receptacle, with the opening provided with means which will prevent the flow of the treating fluid from reaching any portion of the patient below the receptacle; the receptacle having means whereby it may be adjusted 10 as to height or inclination, or both, to suit the height of the particular patient and the treatment contemplated, and is also provided with means by which the treating fluid may be conveniently discharged for use.

20 The invention is illustrated in the accompanying drawings, in which:

Figure 1 is a view in side elevation of the improved apparatus.

Figure 2 is a partial plan view of the 25 forward portion of the receptacle.

Figure 3 is a section on line 3—3 of Figure 1.

The apparatus comprises a base 1 which may be secured to the floor or other support 30 or may, if desired, be of sufficient size and weight to maintain the apparatus in proper position without liability of tipping. A hollow standard 2 rises from the base and slidably receives the post 3 which is adjust- 35 ably secured in the standard by a hand-operated set-screw 4. The post 3 is provided at its upper end with a head 5 having lateral spaced ears 6 in which is mounted a shaft 7 threaded into one of the ears and passing 40 loosely through the other and having an operating crank or handle 8.

A block 9 has a portion extended between the ears 6 and rotatably supported on the pin 7, so that through proper operation of 45 the handle 8 the block 9 may be locked in various pivotal relations with the head 5. The block 9 above the head 5 is formed with a rectangular opening 10 to slidably receive a similarly formed bar 11, a set-screw 50 12 serving to fix these parts in desired adjustment. The terminals of the bar 11 are

provided with yokes 13 in which is secured the receptacle 14.

The receptacle is of shallow, elongated form, though obviously capable of any size 55 and shape, and has an edge rim 15. One edge of the receptacle is closed by appropriately curving the bottom of the receptacle, and the opposite end, which is normally open, is provided with a removable 60 closure 16 slidably cooperating with the rim 15 and having an end wall which, when the closure is in place, prevents discharge of the contents of the receptacle.

Obviously, the closure may be removed to 65 permit the contents of the receptacle to discharge, as for instance into a convenient basin indicated in dotted lines at 17.

At the end remote from the discharge end, the receptacle is formed with an opening 18 70 of sufficient size to permit the convenient passage therethrough of the head of the patient. Surrounding this opening is a flexible rubber gasket 19 secured in place by a clamping plate 20 removably secured to the 75 bottom of the basin. The gasket is formed with an opening 21 somewhat smaller than the opening 18 and so arranged that when the head of the patient is inserted through the opening and through the gasket, the 80 edges of the gasket opening 21 will fit more or less snugly against the neck of the patient to prevent the passage of any fluid below the bottom of the receptacle.

Obviously, the receptacle may be adjust- 85 ed as to height or inclination, and after the head of the patient has been passed through the openings 18 and 21, the operator may freely use the necessary cleansing or treating fluids without liability of the patient's clothing or person below the head being affected. After treatment, the closure 16 may be removed and the contents of the receptacle discharged.

What I claim to be new is:

1. An apparatus to permit the treatment 95 of human hair, comprising an elongated receptacle formed at its upper edge with guides, and closed at one end, and open at the opposite end, a removable closure for 100 the open end of substantially the same shape in cross section as the cross section shape of

the receptacle, said closure having guides which fit on and slide over the free ends of the guide on the receptacle, the receptacle having an opening formed in its bottom, a resilient gasket formed with an opening of less diameter than the opening in the receptacle with the free edges of the gasket extending inwardly of such receptacle open-

ing, yokes depending from the receptacle, a longitudinal bar connecting the yokes, a support, and means between the support and the bar to permit longitudinal or tilting adjustment of the receptacle. 10

In testimony whereof I affix my signature.

DOROTHY NELSEN TRICKEY.
